STROPPING AND HONING DEVICE

Original Filed Oct. 23, 1931

UNITED STATES PATENT OFFICE

2,053,219

STROPPING AND HONING DEVICE

George J. Ganzert, Cliffside, N. J., assignor, by direct and mesne assignments, to Interstate Mechanical Products Corporation, a corporation of New Jersey

Application October 23, 1931, Serial No. 570,584
Renewed August 19, 1933

9 Claims. (Cl. 51—65)

This invention relates to stropping and honing. Principal objects of the invention provide a stropping or honing device of simple and rugged construction, of low cost of material and assembly, and of simple insertion and withdrawal of a safety razor blade, and of effectual stropping or honing qualities.

Principal features of the invention reside in the cooperative association of a two-part receptacle, one part termed the tray and the other the cover, and a herein termed carriage member for removably receiving a razor blade, the carriage member being positioned within the tray; to the inner face of the tray and the inner face of the cover are secured flat strips of leather or other suitable stropping medium or of suitable honing composition, the tray and the cover being readily assembled to thereby interpose the carriage member and the therein mounted razor blade, the cover and the tray being arranged for relative reciprocal motion, whereby the carriage member is reciprocated to and fro relative to the two stropping or honing strips, to effect the desired stropping or honing action, and to regulate at will the degree of pressure in the stropping or honing action.

The further particulars of my invention include a blade holder pivotally mounted on the carriage member, resilient means normally biasing the blade holder and therewith the razor blade in non-operative relation relative to the stropping or honing strips, and frictionally effective elements, such as friction oscillating members having flat faces in frictional relationship with the inner faces of the tray and cover and controlling the blade holder to tilt the same in opposing angular directions to relate the opposite cutting edges of the razor blade in proper stropping or honing relation with the stropping or honing strips.

A primary feature of the invention resides in the assembly of cover and tray parts provided with stropping or honing elements, a razor blade carrying carriage freely received within the cover and tray parts, and mechanism interconnecting the carriage relative to the cover and tray parts whereby the pressure between the edges of the razor blade and the stropping or honing elements is regulated at will by pressure applied manually to the cover and tray parts.

Such interconnecting mechanism comprises means pivotally carried by the carriage and having suitable faces arranged to frictionally engage flat faces of the cover and tray, whereby the pressure exerted manually upon the cover and the tray

toward one another regulates at will the pressure effected in the stropping or honing action.

Preferably such pivoted interconnecting means provides for lost motion in its connection with the blade supporting member of the carriage whereby upon cessation of reciprocation between the cover and the tray, the razor blade is instantly returned to neutral position relative to the stropping or honing elements.

Additional features of the invention reside in the construction of the major parts of the invention from flat stock and the formation of the parts by blanking and forming operations.

Further additional features reside in the utilization of Geneva gear wheels, the slots of each Geneva gear wheel effecting mesh relation with the blade holder to afford the desired angular tilting in opposing directions effective upon the reversed reciprocation of the tray and the cover, each slot having sufficient clearance to provide for lost motion, effective upon cessation of relative movement of the tray and the cover, the resilient means, usually a pair of oppositely disposed flat springs, to instantly return the blade holder and therewith the razor blade to non-operative relation with the stropping or honing strips.

Further features and objects of the invention will be more fully understood from the following detail description and the accompanying drawings, in which

Fig. 1 is a perspective view of a preferred form of my invention, the carriage member and a razor blade positioned on the blade holder, being placed within the tray, the cover being shown demounted from the tray and with its inner face turned upwardly;

Fig. 2 is a central sectional elevation on section line 2—2 of Fig. 1, on an enlarged scale; this view shows the blade holder and retained razor blade in non-operative positions and the cover displaced somewhat toward the left-hand side relative to the tray;

Fig. 3 is a central sectional elevation, similar to Fig. 2, but showing the movement of the cover toward the right-hand side, relative to the tray, the blade holder and retained razor blade being shown tilted and in operative relation to the stropping or honing strips;

Fig. 4 is a transverse vertical sectional elevation on section line 4—4 of Fig. 2; and

Fig. 5 is a detail vertical elevation on section line 5—5 of Fig. 4, on an enlarged scale.

As indicated above, my invention is applicable alternatively either for stropping or honing pur-

poses, determined by the selection of the proper medium for the desired purpose. Since the structural relationship of the parts and the manner of operation is generically similar, the stropping 5 or honing medium is hereinafter referred to as of the stropping type, and accordingly reference to the stropping medium in the hereinbelow description of my invention will suffice to describe the honing type.

10 One strip 10 of stropping medium, such as leather, is shown secured to the inner face of the top of the cover 11, and the other strip 12 of the stropping medium is shown secured to the inner face of the tray 13. Each strip 10, 12, is of rectangular configuration and respectively positioned to provide for exposure of the material of the top of the cover and the bottom of the tray, to provide run-ways thereat, as will appear more fully hereinafter. The strips 10, 12, are secured 15 in position by any suitable adhesive, or other procedure.

The cover 11 and tray 13 are provided for ready assembly and disassembly relative to one another and for affording when assembled longitudinal 25 relative movement, effected by grasping the tray with one hand and the cover with the other hand and imparting reciprocal relative motion to and fro. One form of such mounting and dismounting relation is had by providing one longitudinal 30 side 14 of the tray with an outwardly turned flange 15 and the other longitudinal side 16 substantially vertically rectilinear, its upper edge being substantially level with the upper face of the flange 15 of the opposite longitudinal side 35 14, and the left-hand end 17 and the right-hand end 18 of the tray of reduced height, as compared with the longitudinal sides 14, 16.

The cover 11, for the purpose of ready assembly and disassembly relative to the tray 13, is provided with oppositely disposed, longitudinally extending, inwardly turned flanges 19, 20, see Figs. 1 and 4, the longitudinal flanges 19, 20, being preferably related with respect to the plane body portion of the cover 11 to provide the arcuate, downwardly extending longitudinal edge portions 21, 22, whereby upon exerting pressure in the manual reciprocation of the cover 11 and tray 13, the upper face of the outwardly extending flange 15 of the side 14 of the tray 13 and the upper edge of the longitudinal side 16 of the tray 13 engage such arcuate portions 21, 22, respectively to afford a hinged connection for the assembly of the cover and the tray, and a reliable interlocking relationship during the stage of reciprocation of 50 the cover and the tray, and also the ready disassembly of the same.

To enhance the interlocking relationship between the cover and the tray, the spaced teats 23, formed by outwardly pressing the metal of the longitudinal side 13, or other form of lug or protuberance, may be provided. The carriage and its associated blade holder may be formed of any suitable construction, an essential feature being the provision of frictional relationship between the blade holder in both respect to the cover and the tray when assembled, the carriage having been placed within the tray, whereby upon application of manual force exerted by the hands of the user upon the cover and the tray and the to and fro reciprocation of the same relative to one another, the blade holder is tilted in proper stropping relation relative to the stropping elements and the carriage is bodily reciprocated within the tray.

75 As on form of carriage assembly, I provide the

rectangular frame or carriage member 24 (a detail construction being referred to more fully hereinafter), in which the blade holder 25 is pivotally mounted, a razor blade being indicated at 26, and oppositely disposed frictionally oscillated members or wheels 27 mounted on bearing studs 28, integral or otherwise secured to the carriage member 24. The friction gear wheels 27, 27 have the flat cylindrical or other arcuate surfaces of an effective diameter substantially equal to the 10 clearance between the inner face of the top 11 and the inner face of the tray 13 as provided for in the respective trackways 29, 29, of the tray 13 and trackways 30, 30 of the cover 11, see Figs. 1 and 4.

15 The blade holder 25 may be of any suitable construction, and as illustrated comprises essentially a flat plate, preferably stamped and shaped to provide oppositely extending trunnions 32, initially of the thickness of the plate 20 but folded back upon itself at the terminal portions, see 33; also, preferably, spaced oppositely disposed, extruded lugs 34, 34, received within and to locate the usual correspondingly positioned retaining perforations of present types of 25 razor blades. Additional features of the blade holder 25 are illustrated and referred to hereinafter.

20 Cooperating with the friction gear wheels 27 to attain proper support and positioning of the 30 blade holder 25, the frame of the carriage member 24 comprises the foot elements 35, 35, positioned respectively at opposing corners and oppositely dimensioned to be located in and reciprocated within the two trackways 29, 30; also, 35 an upwardly flanged cross-bar 36 at the end of the frame adjacent the foot elements 35, 35; also a similar upwardly flanged cross-bar 37 at the opposite end of the frame, and opposing, punched bearing openings 38 for receiving the trunnions 40 32 of the blade holder. Such foot elements 35 may be equipped with rollers.

25 The resilient means for biasing the blade holder to its neutral or non-operative position are illustrated as a pair of oppositely related flat 45 springs 39, 39; the free end of each spring being received freely in a horizontal slot 40 suitably formed in a vertically extending tongue 41, formed in the respective longitudinal side flanges 42 of the frame; the fixed end of each flat spring 50 39 is riveted, see 39a, to the lateral edges of the blade holder 25 adjacent to the longitudinal side flanges 42 of the frame of the carriage. Each tongue 41 serves also to limit the angle of tilt 55 of the blade holder to preclude possible withdrawal of its spring 39 from its slot 40.

30 Each longitudinal side flange 42 of the carriage member serves generally to properly locate the carriage member relative to the longitudinal sides 14, 16, of the tray, and the studs 28 for 60 the friction gear wheels 27 are conveniently secured to and project inwardly of these side flanges 42 respectively.

35 The geared relation of each friction wheel 27 with respect to the blade holder 26 may be attained in any suitable manner. A simple and effective arrangement is had by employing each wheel of the Geneva type, see Fig. 5, its radial slot 44 receiving a lateral edge of the flat body portion of the holder 25, its slot 44 being pref- 65 erably outwardly tapered, see 44a, to provide the desired lost motion between the blade holder and each wheel 27, to afford instant biasing of the blade holder to its neutral, i. e., non-operative position and therewith the inserted razor blade 70 75

26, relative to the stropping elements 10, 12, upon cessation of reciprocal movement of the cover and the tray relative to one another.

The razor blade 26 is preferably locked in its inserted position, relative to the blade holder 25, as by means of a clamping plate 45, which preferably is of resilient material, such as spring steel, arched longitudinally and transversely, upwardly flanged at one end 46, to serve as a manipulating element. Cooperating with such clamping plate I provide a locking hook 47, formed as a tongue from the body of the flat body portion of the blade holder 25. Such tongue hook 47 preferably is downwardly extruded, see 15 48, near its free end, to form a downwardly extending lug which is received within a recess 49 formed in the clamping plate 45, and by reason of the resiliency of the plate 45 serves as a snap lock.

20 The operation of my stropping (and honing) device will be largely understood from the foregoing description.

The parts when assembled, prior to reciprocation, assume their positions as illustrated in Fig. 2; upon manually applying reciprocating force to the cover and the tray, say, displacing the cover in the direction of the indicating arrow 50, see Fig. 3, the frictional engagement of each wheel 27 with the respective inner faces of the 25 trackways of the cover and the tray cause each wheel to partially rotate in clockwise direction as viewed in Fig. 3, the blade holder 25 being tilted in counterclockwise direction against the urge of its springs 39, until the opposite edges 30 of the razor blade engage the respective stropping (or honing) strips 10, 12, the continued reciprocation of the cover and the tray causing the carriage to be shifted toward the right, as viewed in Fig. 3.

40 Assuming such displacement of the cover and the tray to be continued, the limit of the movement of the carriage toward the right within the tray is attained by the right-hand end bar 37 of the carriage abutting the end 18 of the tray.

45 Such movement effects a stropping (or honing) of opposite tapered faces of the two edges of the razor blade. The remaining tapered faces of the two razor edges are subjected to stropping (or honing) action upon the reversed displacement 50 of the cover and the tray, and such reciprocation is continued as may be desired.

The degree of stropping (or honing) action is regulated by the degree of pressure exerted by the hands of the user toward one another upon the cover and the tray.

55 In the event that such pressure accompanied by the reciprocation is slight, giving rise possibly to but a partial displacement of the carriage within the tray, the full displacement of the carriage is insured by the downwardly depending end flanges 11a, which clear the end flanges 17, 18, of the tray but engage the respective end bars 36, 37, of the carriage, and displaces the carriage for its full range of movement.

60 65 Upon completion of the stropping or honing operation, the razor blade is removed from the blade holder by grasping the hand hold 46 of the clamping blade 45, to remove the clamp and therewith enable the razor blade to be removed. 70 It is more convenient to remove the razor blade from the carriage, by removing the carriage from the tray. Upon removal of the razor blade from the blade holder, the clamping blade 45 may be replaced, the locking lug 48 serving to retain the

clamping blade 45, the latter as above explained being preferably arched centrally, to insure clamping of the clamping blade notwithstanding the absence of an interposed razor blade.

It will be observed that the ears 51, extending 5 from the oppositely disposed side bars 42 of the frame of the carriage, are effective when the carriage has been removed from the tray, during the operations of insertion and withdrawal of a razor blade, the stops 51 limiting the tilting 10 movement of the blade holder 25 to serve as an abutment for the same, and also serving to preclude withdrawal of the free ends of the biasing springs 39 from their guide slots 40.

From the above, it will be apparent that I have 15 provided a stropping or honing device of especial simple construction of the individual parts and of ready assembly of the parts. It will also be noted, and as is carried out in manufacture, that the majority of parts may be formed of metal, 20 such as cold rolled steel, punched, bent, extruded or otherwise formed to embody the individual constructive features hereinabove described. The metallic parts are protected from corrosion by suitable treatment, as nickel, if of steel or 25 the like, or non-corrodible metal or metal alloy may be employed.

From the above, it will also be apparent that my stropping or honing device embodies a tray, 30 a cover reciprocably mounted relative to the tray, stropping and honing elements respectively secured to the inner faces of the tray and the cover, clearances being provided at the opposite longitudinal edges of the stropping or honing elements to form trackways, and a carriage being 35 interposed between the tray and the cover, the carriage being equipped with a blade holder for tilting the inserted razor blade in opposing directions and further equipped with a movable element, preferably a pair of oppositely disposed 40 oscillated elements, such element or elements being non-mechanically related to the tray and the cover excepting by frictional engagement therewith, thus affording a free, that is to say, a non-fixed mechanical assembly between the 45 carriage, the cover and the tray, such element or elements utilizing such trackways, whereby upon regulated frictional engagement exercised manually coincident with the reciprocated movement of the cover relative to the tray, the stropping 50 or honing effect is attained, and with the desired degree of pressure of the respective faces of the opposite shaving edges of the razor blade upon the stropping or honing elements.

Whereas I have illustrated the connection between the movable element and the blade holder as comprising a gear provided with a slot for directly receiving the blade holder, to effect the opposing tilting operation, it will be understood that other forms of gearing may be employed in 60 lieu thereof.

Whereas I have described my invention by specific reference to various forms thereof, it will be understood that many changes and modifications may be made without departing from 65 the spirit of the invention.

I claim:

1. In a stropping or honing device, the combination of a tray, a cover reciprocably mounted relative to said tray, said cover and said tray being 70 movable toward and from each other, stropping or honing elements respectively secured to the inner faces of said tray and said cover, clearances being provided at opposite longitudinal edges of said stropping or honing elements, a carriage 75

arranged to be disposed within said tray, means on said cover for reciprocating the carriage longitudinally of the tray, a pair of pivoted elements having faces for supporting said carriage, a blade holder for removably receiving a razor blade, and spring means connecting said pivoted elements with said blade holder for effecting the tilting and for regulating at will the pressure of said blade holder and therewith of the inserted blade 10 relative to the stropping or honing elements.

2. In a stropping or honing device, the combination of a cover, a tray reciprocably mounted relative to said cover, a carriage for supporting a razor blade, said carriage being received within 15 said tray, said carriage including a movable member engaging and displaceable relative to said tray and said cover, upon pressure manually applied to said tray and said cover controlled by said movable member, lost motion means interposed between said tiltable blade 20 holder and said movable member, resilient means normally biasing said blade holder to its neutral position, and stropping or honing elements carried by said tray and said cover.

3. In a stropping or honing device, the combination of a cover, a tray reciprocably mounted relative to said cover, a carriage for supporting a razor blade, said carriage being received within 25 said tray, said carriage including a rotatable member engaging and displaceable relative to said tray and said cover, upon pressure manually applied to said tray and said cover, said carriage further including a tiltable blade holder controlled by said rotatable member, lost motion 30 means interposed between said tiltable blade holder and said movable member, resilient means normally biasing said blade holder to its neutral position, and stropping or honing elements fixedly carried by said tray and said cover.

4. In a stropping or honing device, the combination of a cover, a tray reciprocably mounted relative to said cover, a carriage for supporting a razor blade, said carriage being freely received within 35 said tray, said carriage including a pair of oppositely disposed movable members respectively engaging and displaceable relative to said tray and said cover, upon pressure manually applied to said tray and said cover, said carriage further including a tiltable blade holder controlled by said movable members, lost motion 40 means interposed between said tiltable blade holder and said movable member, resilient means normally biasing said blade holder to its neutral position, and stropping or honing elements fixedly carried by said tray and said cover.

5. In a stropping and honing device, a tray, a cover, said tray and said cover being reciprocably related to one another, stropping or honing elements, carried by said tray and cover respectively, a carriage mountable within said tray, pivoted means carried by said carriage, and displaceable upon pressure applied to said cover and said tray, a flat plate pivotally mounted on said carriage for supporting a razor blade, lost 55 motion means interposed between said rotary means and said flat plate, resilient means normally biasing said flat plate toward its neutral position, and connection means including lost motion means between said flat plate and said 60 pivoted means for tilting said flat plate in opposing directions upon opposite directions of reciprocation of the cover and tray, whereby the pressure between the razor blade and said stropping or honing elements is regulated at will by 65 the pressure applied to the cover and the tray.

6. In a stropping or honing device, the combination of a cover, a tray reciprocably mounted relative to the cover, a carriage for supporting a razor blade, said carriage being received within the tray, movable means subject to pressure exerted manually upon the cover and the tray for regulating at will the pressure imparted to the razor blade, lost motion means interposed between said movable means and the razor blade, and stropping or honing elements carried by the 10 tray and the cover. 5

7. In a stropping or honing device, the combination of a tray, a stropping or honing element carried on the inner face of said tray and extending longitudinally thereof, said tray having a flat face portion extending longitudinally of the stropping or honing element, a cover, a stropping or honing element carried on the inner face of the cover and extending longitudinally thereof, the inner face of said cover having a flat face 20 portion extending longitudinally of its stropping and honing element, a carriage, means for tiltingly mounting a razor blade in said carriage, movable means carried by said carriage including lost motion means affecting the extent of tilt 25 of said razor blade mounting means, said movable means engaging the flat face portion of the inner face of said tray and the flat face portion of the inner face of said cover, and means loosely and detachably interconnecting said cover and 30 said tray to afford reciprocation of said cover and said tray relative to one another and to dually afford at will movement of said cover and said tray toward or from one another.

8. In a stropping or honing device, the combination of a tray, a stropping or honing element carried on the inner face of said tray and extending longitudinally thereof, said tray having a flat face portion extending longitudinally of the stropping or honing element, a cover, a 35 stropping or honing element carried on the inner face of the cover and extending longitudinally thereof, the inner face of said cover having a flat face portion extending longitudinally of its stropping and honing element, a carriage, means for tiltingly mounting a razor blade in said carriage, pivotally movable means carried by said carriage including lost motion means affecting the extent of tilt of said razor blade mounting means, said movable means engaging the flat 40 face portion of the inner face of said tray and the flat face portion of the inner face of said cover, and means loosely and detachably interconnecting said cover and said tray to afford reciprocation of said cover and said tray relative 45 to one another and to dually afford at will movement of said cover and said tray toward or from one another.

9. In a honing or stropping device, the combination of a tray, a stropping or honing element carried on the inner face of said tray and extending longitudinally thereof, said tray having a flat face portion extending longitudinally of the stropping or honing element, a cover, a stropping or honing element carried on the inner face of the cover and extending longitudinally thereof, the inner face of said cover having a flat face portion extending longitudinally of its stropping and honing element, a carriage, means for tiltingly mounting a razor blade in said carriage, 60 movable means carried by said carriage including resilient means, a housing for one end of the resilient means and in which the resilient means is freely slidably, said resilient means and housing 65 cooperating to affect the extent of tilt of said 70 razor blade, and means for supporting the housing of the resilient means.

razor blade mounting means, said movable means engaging the flat face portion of the inner face of said tray and the flat face portion of the inner face of said cover, and means loosely and detachably interconnecting said cover and said tray to afford reciprocation of said cover and said tray relative to one another and to dually afford

at will movement of said cover and said tray toward or from one another, said cover and tray interconnecting means including stops for limiting the extent of their relative reciprocal movement.

GEORGE J. GANZERT.
